ATTORNEY

UNITED STATES PATENT OFFICE.

CHARLES SCHERER, OF BROOKLYN, ASSIGNOR TO MORRIS RUBENS, OF NEW YORK, N. Y.

POCKET-BOOK FRAME.

SPECIFICATION forming part of Letters Patent No. 251,645, dated December 27, 1881.

Application filed October 19, 1881. (No model.)

To all whom it may concern:

Be it known that I, CHARLES SCHERER, of Brooklyn, in the county of Kings and State of New York, have invented certain new and useful Improvements in Pocket-Book Frames, of which the following is a specification.

This invention relates to an improved pocket-book frame by which the book may be opened or closed with great facility.

10 In the accompanying drawings, Figure 1 represents a perspective view of a pocket-book with my improved pocket-book frame. Figs. 2 and 3 are detail vertical transverse sections of the frame, showing it respectively in closed and open position; and Figs. 4 and 5 are a perspective view and a vertical transverse section of a modified construction of the frame.

Similar letters of reference indicate corresponding parts.

20 Referring to the drawings, A represents a covered pocket-book frame of the well-known construction, composed of two jaws, *a* *a'*, and a cover or guard, *b*, extending over the jaw *a*. To the covering or guard *b* is applied a raised bridge, *d*, which is provided with a recess or indentation, *d'*. A V-shaped spring-clasp, *e*, is riveted at one end to the jaw *a'*, its outer free end being provided with a handle or thumb-rest, *e'*. The upper part or leg of the clasp *e* 25 is provided with a raised bead or stud, *e''*, which springs into the recess or indentation *d'* of the bridge when the jaws are closed. If desired, the bridge may also be arranged in a barreled

frame by recessing the barrel, as shown in Figs. 4 and 5. The spring-clasp may also lock to 35 the frame below the covered jaw, in which case the cover itself forms the bridge-piece.

The frame A is readily opened by pressing with the thumb upon the outer handle or rest of the clasp *e*, so that its projecting catch *e''* is 40 withdrawn from the hole or indentation *d'* of the bridge *d*, and thereby the book opened. The book is readily closed by pressing the jaws together, by which the spring-clasp is locked to 45 the bridge in a reliable manner. The book may thus be readily opened or closed while holding it in the hand, and thereby a neat and simple locking device for pocket-book frames furnished.

Having thus described my invention, I claim 50 as new and desire to secure by Letters Patent—

The combination, in a pocket-book frame, of the hinged jaws *a* and *a'*, the guard *b*, attached to jaw *a*, the bridge *d*, attached to the guard, and the V-shaped spring-clasp *e*, projecting laterally from the jaw *a'*, and provided with a catch adapted for connection with the bridge of jaw *a*, substantially as described.

In testimony that I claim the foregoing as my invention I have signed my name, in presence of two witnesses, this 5th day of October, 1881.

CHARLES SCHERER.
